DOZER-BLADE MOUNTING.

Lloyd Thurman Graves, North Vancouver, British Columbia, Canada, assignor of one-half to William Blaylock Steele, Vancouver, British Columbia, Canada

Application December 27, 1950, Serial No. 202,839

8 Claims. (Cl. 37—144)

This invention relates to a dozer-blade mounting, and for its general object aims to provide a perfected mounting which enables the blade to be easily and quickly located in selected settings within a wide range of adjustment comprehending (1) angling of the blade about a vertical axis in either direction from a normal centered position, (2) tilting of the blade about a horizontal axis in either direction from a normal centered position, (3) bodily vertical movement, and (4) compounds of these described motions.

It is a further and particular object to provide, in conjunction with a dozer blade of this nature, power-driven devices for moving the blade into said adjusted positions and controlled from a position conveniently accessible to an operator driving a tractor or other like vehicle to which the dozer blade is attached.

It is a still further object to provide a structure in which the dozer blade takes its support from a swing-frame pivotally attached to the tractor; and having means in association with such swing-frame capable of so resisting torsional forces passed from the blade into the frame as to positively safeguard the frame against liability of twist.

The foregoing and other still more particular objects and advantages in view will appear and be understood in the following description and claims, the invention consisting in the novel construction and in the adaptation and combination of parts hereinafter described and claimed.

In the accompanying drawings:

Figure 1 is a view in side elevation portraying a tractor and dozer-blade assembly with the mounting for the dozer blade constructed in accordance with the preferred teachings of the present invention.

Fig. 2 is an elevational view looking at the assembly from the side opposite that in which it is viewed in Fig. 1 and also deleting the near crawler track in order to fully expose the swing-frame which carries the dozer blade.

Fig. 3 is a fragmentary horizontal sectional view on line 3—3 of Fig. 1.

Fig. 4 is a fragmentary side elevational view drawn to an enlarged scale and detailing the dozer blade and a portion of the swing-frame.

Fig. 5 is a transverse vertical section on line 5—5 of Fig. 3.

Fig. 6 is a fragmentary longitudinal vertical section on line 6—6 of Fig. 3.

Fig. 7 is a fragmentary longitudinal vertical section drawn to an enlarged scale on line 7—7 of Fig. 5.

Fig. 8 is a transverse vertical section drawn to an enlarged scale on line 8—8 of Fig. 1.

Fig. 9 is a fragmentary longitudinal vertical section on line 9—9 of Fig. 8; and

Figs. 10, 11 and 12 are schematic illustrations viewing the tractor and dozer-blade assembly from the side, from the top, and from the front, respectively, to portray in Fig. 10 the bodily vertical adjustment, in Fig. 11 the angling adjustment, and in Fig. 12 the tilting adjustment.

The dozer blade of the present invention is designated by the numeral 15 and is shown in association with a crawler-type tractor. The tractor which I have elected

2

to portray is of that type developed by Peter Fisher and illustrated and described in pending application for Letters Patent of the United States filed May 1, 1950, Ser. No. 159,311. Cursorily considered, said tractor provides a main frame including spaced-apart longitudinal side principals 16 and 17, and has its "self-laying" tracks 18 carried by crawler-frames 20 which are independently journaled for oscillatory motion about pivot bearings 21 provided at each side of the main frame, these pivot bearings being located more or less central to the over-all length of the crawler-frames. This particular tractor provides comparatively high clearance below its front-end engine 22, and while some of the teachings of the present invention could feasibly be applied to that type of dozer-blade mounting in which swingably mounted supporting beams lie outside the crawler tracks, it is self-evidently more desirable to employ, as a support for the blade, a swing-frame located to the inside of the crawler tracks. Clearance is of course vital to such a location. The swing frame which I prefer to employ is one employing a longitudinal tongue projecting forwardly on the substantial longitudinal median line of the tractor from a cross-bar 24 having its ends pivotally journaled in pillow-blocks 25 and 26 bolted to the underside of the main frame principals 16 and 17, respectively. The free end of the tongue extends beyond the front-end limit of the tracks and has a tree fixedly secured thereto. Excepting for the presence of gussets 30 which reinforce the angles, the tree has a general T-shape in plan configuration with the cross member or plate 31 of the T lying to the front and being composed by preference of plate stock. The leg 32 of the T extends rearwardly on the longitudinal median line of the swing-frame, and is comprised of a cylinder member open at both ends with its front end fitted in a hole which pierces the plate. The components of the tree, and namely the plate 31, cylinder member 32, and the gussets 30 are integrally connected by weld joints, and also made an integral part of this tree is a centrally placed projection 34 rising from the plate 31 and suitably reinforced at the front by a vertical rib 33. At its upper end this projection presents a forwardly projecting transversely sloped flange 35, and for a purpose which will be hereinafter described the flange has a surmounting boss 36 welded thereto. The tongue of the swing-frame is made rigid both with the cross-bar 24 and with the tree and, as with the components of the tree, welding is employed at the connecting joints. The tongue is composed of pipe-struts 40 and 41 extending diagonally inwardly from the cross-bar 24 to the cross-member 31, and has two thills 42 and 43 extending from said cross-bar to the cylindrical leg 32 and lying parallel to one another at opposite sides of the latter. A hydraulic cylinder 44 is welded between these thills to have its axis coincide with that of the cylindrical leg, and received in this hydraulic cylinder is a double-acting ram 45 coupled by a connecting rod 45 to a pipe 46 fitted for slide movement in the bore of said leg, the pipe projecting by its front end forwardly well beyond the leg. At the front end of the tractor there is erected from each of the two frame principals 16 and 17 a respective superstructure, as 47 and 48, and occupying an overhead position with its ends journaled in post elements provided by these superstructures there is provided a transverse rock-shaft 50. Twin lever arms 51 and 52 are welded to the rock-shaft at opposite sides of the longitudinal median line of the tractor to have their free ends extend forwardly into overhanging relation to the tree, and extending downwardly from these free ends to underlying ears 53 and 54 which are welded to the tree's cross-member 31 there are provided connecting tie-rods 55 and 56, respectively. One end of the rock-shaft protrudes laterally beyond its supporting post, and for rocking the rock-shaft there is welded upon this protruding end a power

arm 57 attached by a connecting rod 58 to a double-acting hydraulic ram, the ram working in a pivotally-mounted cylinder 59. The two lever arms 51 and 52 each serve in conjunction with the power arm 57 to produce a substantial bell-crank, and it will be apparent that the use of two such bell-cranks, in complement with the two tie-rods, effectively stiffens the swing-frame against liability of torsional twist.

The dozer blade is provided with rigid horizontal backing ribs 60 and 61 disposed in parallel spaced relation and each comprising a piece of plate stock welded by an edge to the blade. On the substantial minor axis of the blade and equidistantly spaced therefrom toward each side edge of the blade the two ribs are vertically pierced with sets of registering holes operating to receive headed kingpins, as 62, 63 and 64. The center king-pin 62 is arranged to establish a pivot connection from the dozer blade to the projecting end of the pipe 46, and for this purpose there is welded as a cross-arm upon the head of the pipe a through-bored knuckle 65 of a length to fit more or less snugly between the ribs 60 and 61. The king-pins 63 and 64 each act to pivotally engage the arms of a respective clevis 66 (see Fig. 6). These clevises project rearwardly beyond the exposed edges of the backing ribs and bear by their back faces against pads 67 which are pivotally attached by king-pins 68 to the cross-member 31 of the tree, the king-pins being received through bearing blocks 70 welded as integral adjuncts of said cross-member. From the pad 67 yoke-arms 71 extend forwardly along opposite sides of the related clevis 66, and traversing these yoke-arms 71 to confine the cross-arm 69 of the clevis is a horizontal shackle-bolt 72 screwed or otherwise held in place and removable at will to free the clevis from the restraining yoke-arms 71. As will perhaps be best seen from an inspection of Fig. 4 the span from the upper to the lower leg of the clevis 66 is comparatively wide so as to leave the shackle-bolt 72 relatively unfettered insofar as vertical play is concerned and thus permit the dozer blade to be pivoted about the center of the pipe 46 as an axis into positions tilted with respect to the swing-frame. Also significant in respect of such tilting action is the fact that the vertical cross-arm 69 of the clevis is given a greater width than the width of the two horizontal legs whereby to maintain an assured clearance between the legs and the yoke arms 71 and preclude the former from hanging up as the clevis moves vertically relative to the pad.

For accomplishing the tilting motion of the blade a surmounting boss 73 is welded or otherwise integrally secured to the backing rib 60 to occupy a position adjacent a side-edge limit of the blade, and journaled for swivel movement in this boss 73 is a knuckle 74. A complementing knuckle 75 is similarly swivel-mounted in the boss 36 which surmounts the forwardly projecting flange 35 of the projection 34. Attached by a pivot pin 76 to one of these knuckles, say the knuckle 74, is the connecting rod 77 of a double-acting ram, and a hydraulic cylinder 78 in which this ram works is connected by a pivot pin 80 to the other knuckle 75.

From the foregoing description it will be seen that there are three double-acting hydraulic rams each functional upon the dozer blade. One of these rams, and namely the ram working in the cylinder 78, performs the described tilting action. A second said ram, and namely the ram working in the cylinder 59, acts through the twin bell-cranks to raise and lower the swing-frame which, perforce, raises and lowers the blade bodily. The third ram, and namely the ram working in the cylinder 44, acts through the pipe 46 to move the main knuckle connection 65 of the dozer blade directly toward and from the swing-frame. Forward motion given to this knuckle-joint is performed only when one or the other of the two shackle-bolts 72 have been first removed, whereupon the blade, having its other end still shacked to the swing-frame, will swing about this shackle connection as a fulcrum and locate itself diagonal to the longitudinal median line of the tractor. While it is eminently desirable to employ hy-

draulic energy in angling the dozer blade about either of said end shackles as a fulcrum, the hydraulic ram which performs this operation can be dispensed with, in which case the work of moving the blade about its end shackle 5 as a fulcrum is performed by lowering the blade onto the ground and inching the tractor either forwardly or backwardly as the desired blade movement dictates. In the absence of the hydraulic lock which the ram provides, the blade is or may be suitably fixed at selected variable degrees of angularity by having the pipe pierced with a series of longitudinally spaced holes, and in the cylindrical leg 32 which forms a journal for such pipe providing diametrically opposite circumferentially extending slots with which the holes may be selectively brought into register, 10 then dropping an anchoring pin through the registering openings. The purpose of the slots, as distinguished from a round hole, is to enable the pipe and its anchoring pin to swivel in compensation of tilting movements given to the dozer blade.

15 The two ports through which fluid under pressure is fed to the ends of the respective hydraulic cylinders are connected by flexible hoses, as 81—82, 83—84, and 85—86, with the valved chests of a control box 87, and this control box may be advantageously mounted upon a bracket 20 25 30 35 secured to one of the two superstructures to occupy a position at the side of the tractor opposite the hydraulic cylinder 59. The hydraulic fluid may be either air or oil, the latter by preference, and such fluid is supplied under pressure to the valve chests from a pump or the like (not shown) driven by the engine of the tractor. The circuit and the arrangement of the control valves being such, upon a centering of the valves, as to enable the related rams to be held in selected positions by producing a hydraulic lock. Control handles 89, 90 and 91 conveniently accessible to the operator of the tractor are operatively connected with the valves 92, 93 and 94, respectively, of the three chests.

It is thought that the invention and the manner of its 40 45 operation will have been clearly understood from the foregoing detailed description of the now preferred embodiment of my invention. Minor changes in the details of construction will largely suggest themselves and it is my intention that no limitations be implied and that the hereto annexed claims be given a scope fully commensurate with the broadest interpretation to which the employed language admits.

What I claim is:

1. In combination with a tractor, and a dozer blade 50 55 60 65 70 75 therefor, a longitudinally disposed cylinder member firmly supported by the tractor to occupy a laterally centered position at the front end thereof, a stud journaled for endwise sliding movement in the bore of the cylinder and provided upon its front end with an exposed knuckle, a king-pin connecting said knuckle with the blade, a pair of individually releasable connecting couples between the blade and means carried by the tractor oppositely laterally removed from the knuckle and functioning as selective fulcrums about which the blade swings as the knuckle is advanced or retracted longitudinally of the tractor by endwise movement given to the stud, and means for setting said stud at selected points within the limits of its slide movement, each of said connecting couples including a clevis, a connecting member providing a pad at one end having a pair of yoke arms extending from its inner end and located at opposite sides of the clevis, a removable shackle bolt extending through said yoke arms and between the legs of the clevis, and king pins connecting the free ends of the legs of the clevis and the outer end of the connecting member to the dozer blade and the means carried by the tractor, respectively.

2. A mounting for a dozer blade comprising, in combination with a supporting frame, an open-front cylinder member rigidly secured to the frame to locate its axis 75

on the longitudinal median line of the frame, a stud receiving a slide and rotary journal in said cylinder member and projecting forwardly therefrom, said stud being provided at the front end with a rigid vertically bored head, means fixed to the back of the blade and acting in complement with the head of the stud and an associated king-pin to establish a knuckle joint between the blade and the stud, hitch connections between the blade and the frame laterally spaced from opposite sides of the knuckle joint, and means adjustable as to length and extending as a tie from a frame-carried projection overlying the knuckle joint to a blade-carried fitting laterally offset from the knuckle joint, means being provided for setting the stud at selected adjusted positions within prescribed limits of its permitted slide movement within the cylinder member.

3. The structure of claim 1 in which the distance between the legs of the clevis appreciably exceeds the diameter of the shackle bolt.

4. The structure of claim 1 in which the width of the legs of the clevis is less than the width of the cross-arm portion of the clevis.

5. In combination with a tractor, and a dozer blade therefor, a rigid swing-frame received between the traction processes of the tractor with its inner end supported by the tractor for vertical swinging movement of the free outer end about said inner end as an axis and with said free end projecting forwardly beyond the front end of the tractor, a cylinder rigidly supported by said swing-frame to locate its axis on the longitudinal median line of the tractor, a piston received for endwise sliding movement in the cylinder, a piston rod connected with the piston and extending forwardly therefrom beyond the front-end limit of the swing-frame and upon its front end carrying an exposed knuckle which is mounted for swivel movement about an axis which is fixed with respect to the swing frame in the approximate longitudinal median plane of the tractor, a king-pin connecting said knuckle with the blade, manually controlled power-driven means receiving support from the tractor and operatively interconnected with said free end for raising and lowering the swing-frame, a pair of individually releasable connecting couples between the blade and the swing-frame laterally removed to opposite sides from the knuckle and functioning as a selective fulcrum about which the blade swings as the knuckle is advanced or retracted longitudinally of the tractor by endwise movement given to the piston, means for tilting the blade in a vertical direction about the swivel axis of the knuckle and characterized in that one part of said means is connected to the blade and another part thereof is mounted for co-incident vertical movement with the swing-frame, and means for setting said piston at selected points within the limits of its slide movement.

6. In combination with a tractor, and a dozer blade therefor, a rigid swing-frame received between the traction processes of the tractor with its inner end supported by the tractor for vertical swinging movement of the free outer end about said inner end as an axis and with said free end projecting forwardly beyond the front end of the tractor, a cylinder rigidly supported by said swing-frame to locate its axis on the longitudinal median line of the tractor, a piston received for endwise sliding movement in the cylinder, a piston rod connected with the piston and extending forwardly therefrom beyond the front-end limit of the swing-frame and upon its front end carrying an exposed knuckle which is mounted for swivel movement about an axis which is fixed with respect to the swing frame in the approximate longitudinal median plane of the tractor, a king-pin connecting said knuckle with the blade, manually controlled power-driven means receiving support from the tractor and operatively interconnected with said free end for raising and lowering the swing-frame, a pair of individually releasable connecting couples between the blade and the swing-frame laterally

removed to opposite sides from the knuckle and functioning as a selective fulcrum about which the blade swings as the knuckle is advanced or retracted longitudinally of the tractor by endwise movement given to the piston, and means for tilting the blade in a vertical direction about the swivel axis of the knuckle and characterized in that one part of said means is connected to the blade and another part thereof is mounted for co-incident vertical movement with the swing-frame.

10 7. In combination with a tractor, and a dozer blade therefor, a rigid swing-frame received between the traction processes of the tractor with its inner end supported by the tractor for vertical swinging movement of the free outer end about said inner end as an axis and with said free end projecting forwardly beyond the front end of the tractor, a knuckle arranged to lie to the front of the swing-frame and journal-mounted from the latter for fore-and-aft-movement on the longitudinal median line of the tractor and also for swivel movement about said median line as an axis, means for moving said knuckle to selected adjusted positions within the limits of its permitted fore-and-aft movement, a king-pin connecting said knuckle with the blade, manually-controlled power-driven means receiving support from the tractor and operatively interconnected with said free end of the swing-frame for raising and lowering the latter, a pair of individually releasable connecting couples between the blade and the swing-frame laterally removed to opposite sides from the knuckle and functioning as a selective fulcrum about which the blade swings as the knuckle is advanced or retracted longitudinally of the tractor, and means for tilting the blade in a vertical direction about the swivel axis of the knuckle and characterized in that one part of said means is connected to the blade and another part thereof is mounted for co-incident vertical movement with the swing-frame.

20 8. In combination with a tractor, and a dozer blade therefor, a rigid swing-frame having its inner end pivotally supported by the tractor for vertical swing movement of the free outer end about said inner end as an axis and with said free end projecting forwardly beyond the front end of the tractor, a knuckle arranged to lie to the front of the swing-frame and journal-mounted from the latter for fore-and-aft movement in the longitudinal median plane of the tractor and also for swivel movement about an axis which is fixed with respect to the swing-frame in said median plane, means for moving said knuckle to selected adjusted positions within the limits of its permitted fore-and-aft movement, a king-pin connecting said knuckle with the blade, manually-controlled power-driven means receiving support from the tractor and operatively interconnected with said free end of the swing-frame for raising and lowering the latter, a pair of individually releasable connection couples between the blade and the swing-frame laterally removed to opposite sides from the knuckle and functioning as a selective fulcrum about which the blade swings as the knuckle is advanced or retracted longitudinally of the tractor, and means for tilting the blade in a vertical direction about the swivel axis of the knuckle and characterized in that one part of said means is connected to the blade and another part thereof is mounted for co-incident vertical movement with the swing-frame.
